UNITED STATES PATENT OFFICE.

WILLIAM H. YOUNG AND RALPH P. WILTON, OF WRIGHTSVILLE, PENNSYLVANIA;
SAID YOUNG ASSIGNOR TO SAID WILTON.

COIN-PACKAGE.

1,076,474.

Specification of Letters Patent. Patented Oct. 21, 1913.

Application filed November 9, 1911. Serial No. 659,453.

To all whom it may concern:

Be it known that we, WILLIAM H. YOUNG and RALPH P. WILTON, citizens of the United States, residing at Wrightsville, county of 5 York, and State of Pennsylvania, have invented new and useful Improvements in Coin-Packages, of which the following is a specification.

This invention relates to a coin package 10 or holder, and more particularly to a device for packaging coins for transportation or for convenience in storing, the holder being so constructed as to disclose to view sufficient of the coins to admit inspection as to 15 the denomination and genuineness of the coins.

The invention contemplates a holder such that it may be readily filled and emptied without breaking the package, disassembling any of its parts, or loosening any fastening devices, the holder being of predetermined length and size to accommodate a certain number of coins of a given denomination to facilitate the counting of a large 25 number of the coins in banks, and the like.

Further, the improved holder aims at the provision of a structure wherein the coins completely fill the same, and wherein the end walls are uninterrupted or unbroken 30 and lie snug against the coins at the ends of the package to protect them from contact with the movable parts of the holder.

The invention still further aims at the provision of a coin holder, which may be 35 adjusted to support the coins on edge, and in such position that the coins may be readily and quickly withdrawn singly from the package for distribution in making change at box-windows of theaters, or the like, 40 where economy in time is necessary.

The invention embodies a coin holder which essentially comprises a pair of receiving members which are transversely curved to snugly fit against the opposed edges of 45 the coins, and being of a width sufficient only to hold the coins from edgewise displacement, these receiving members being held in opposed position by overlapping arms which are pivoted, and which extend 50 across the faces of the coins at the end of the package, the arms carrying frictional locking means for holding them closed during the transportation of the package.

Other objects and advantages will be 55 brought out in the following detail descrip-

tion of one embodiment of the invention, which is disclosed in the annexed drawing, in which—

Figure 1 is a perspective view of the improved holder, showing coins supported in 60 position, Fig. 2 is a longitudinal sectional view through one end of the same, showing the holder partly closed, Fig. 3 is a detail sectional view on the line 3—3 of Fig. 2. Fig. 4 is a sectional view on the line 4—4 65 of Fig. 5, showing one end of the holder closed. Fig. 5 is a transverse section through the holder on the line 5, 5 of Fig. 4. Fig. 6 is a transverse sectional view on the line 6—6 of Fig. 7, showing the position of the 70 coins when the holder is closed. Fig. 7 is a top plan view of the complete holder closed and being filled with coins. Fig. 8 is an end elevation of the improved holder resting upon a table or other flat surface, and being 75 open to admit of the withdrawal of the coins. Fig. 9 is a side elevation of the same. Fig. 10 is a plan view of a slightly modified form of the invention. Fig. 11 is a plan view of the coin holding members of Fig. 80 10 separated. Fig. 12 is a detail sectional view of the frictional locking means of the modified form.

Referring to the drawings, in which similar parts are designated by like characters 85 of reference in the several views, 10 and 11 designate a pair of receiving members. Each of the members 10 and 11 is preferably formed from a length of metal curved transversely and being relatively narrow, 90 so as to fit snugly against the edges of the coins 12, and to extend but a short distance around the edges of the same. The members 10 and 11 are of a width sufficient only to retain the coins 12 from displacement when the members are diametrically opposed. The member 10 is provided at each end with an inwardly extending arm 13, which is rounded at its outer end, as at 14, to snugly 95 fit against the inner wall of the opposed receiving member 11. The arm 13 is provided with opposed concaved edges reducing the width of the arm at its intermediate portion, for the purpose of displaying the outer side of the end coin which rests snugly 100 against the arm. A slot 15 is formed midway of the edges of the arm 13 and at its inner end adjacent the receiving member 10, for a purpose hereinafter disclosed. The opposed receiving member 11 is slightly 105 110

longer than the member 10, and carries a pair of inwardly extending arms 16 overlapping against the outer sides of the arms 13 and have their opposed edges concaved to register flush with the edges of the arms 13 when the holder is closed. The arms 16 are rounded at their outer ends, as at 17, and extend into flush relation with the outer face of the receiving member 10. Inturned from the outer ends of the arms 16 and midway of their lateral edges are projections or lugs 18, which register with and engage into the slots 15.

From Fig. 3 it will be noted that the opposed edges of the projections 18 are inclined or beveled, so as to permit of the forcing of the same out of the slots 15, when considerable pressure is applied to the arms 16 to move the same about the pivotal connecting rivet 19. The rivet 19 passes through the intermediate portions of the arms 13 and 16, not only pivotally connecting the arms to each other, but also compressing the arms, so as to yieldingly hold the projections 18 in the slots 15.

In Fig. 1 the coin holder is disclosed in adjustment for supporting a number of coins on edge upon a counter, table or the like. It will be noted that the arms 13 and 16 are turned past each other to such an extent that the inturned lugs or projections 18 engage the upper edges of the inner arms 13 and act as stops to hold the arms in such cross relation. When the arms are thus positioned, the receiving members 10 and 11 are not diametrically opposed, but approach one another at the lower side, the lower edges of the receiving members resting upon the counter or table to support the coins 12 in upright position. Since the upper edges of the members 10 and 11 are now spread apart, the coins 12 can be readily pulled upwardly out of the holder, one at a time.

In packaging coins the holder is adjusted as is disclosed in Fig. 1, and then filled with the coins, the end coins fitting snugly against the inner uninterrupted sides of the arms 13. The receiving members 10 and 11 are now raised whereupon the projections 18 are forced against the upper edges of the arms 13, and the inclined edges of the lugs 18 slide against the arms 13 and spring the free ends of the outer arms 16 away from the inner arms 13. During this springing movement the projections 18 bear against the outer faces of the arms 13 and hold the arms in such sprung relation until the projections are brought into registration with the slots 15. The projections 18 snap into the slots 15 and yieldingly hold the arms in such registered position. The receiving members 10 and 11 are now diametrically opposed and, by reason of their curvature, their opposite edges retain the

coins 12 from lateral displacement from the package.

From the above description it will be observed that the package is opened simply by exerting sufficient pressure upon the members 10 and 11 to bring the same together against the tension of the outer ends of the arms 16 so as to raise the projections 18 out of the slots 15. In Fig. 2, the arms 13 and 16 are disclosed as being partially closed. In this instance the projection 18 is disclosed as bearing against the outer face of the arm 13 so as to hold the outer end of the arm 16 away from the arm 13. From Fig. 4 it will be observed that when the projection 18 registers with the slot 15, the outer end of the arm 16 springs inwardly and lies flat against the arm 13, thus yieldingly holding the projection 18 in the slot. The resiliency of the outer ends of the arms 16 is adapted to be such as to hold the projections 18 from displacement under ordinary pressure exerted against the receiving members 10 and 11, but admitting of the raising of the projections from the slots 15 when a slightly increased pressure is applied to the receiving members.

In Figs. 10, 11 and 12 a slight modification of the invention is disclosed, wherein each of the coin holding members is formed of the receiving members 10' and 11', which are of equal length and are provided with inwardly extending arms 13' and 16'. When these coin holding members are assembled, as disclosed in Fig. 10, the arms 13' and 16' are arranged in such overlapping relation that at one end of the holder the arm 13' is on the outside, while at the opposite end of the holder this arm 13' is on the inner side. This arrangement is suggested in the disassembled view Fig. 11.

The member 10' is provided at one end with a notch or slot 15', and the arm 13' at the opposite end of the member 10' is provided at its extreme outer edge with an inturned lug or projection 18'. The lug or projection 18' is preferably formed by prolonging the arm 13' at its end and between its edges in the shape of the projection, which is turned inwardly. In a similar manner the coin receiving member 11' is provided at one end with the slot 15', and the arm 16' at the opposite end of the member 11' carries a lug or projection 18'. With this arrangement when the coin holding members are assembled the lugs or projections are brought into registration with each other, since they are formed upon the opposite ends of the members and the arms. The arms 13' and 16' are pivoted in pairs, as in the preferred form, upon the rivets 19. The advantage of the structure disclosed in this modification is that in the manufacture of these devices it is necessary only to provide a single set of dies, since the members 10' 130

and 11' are similar in length and are formed alike. There is also an advantage in notching the end of the member 10' in place of forming the slot in the end of the arm, since the lug or projection 18' may be turned inwardly from the extreme edge of the opposite arm to a better advantage than in cutting away the end of the arm to provide the projection. The operation of this modified form is similar to the operation of the preferred form, the arrangement of the lugs and slots being substantially the same.

In Figs. 8 and 9 of the drawings, the holder is disclosed as being open and resting upon a table or other flat surface with the lower edges of the members 10 and 11 resting upon the flat surface. The members 10 and 11 are held from upward movement by engagement of the lugs or projections 18 against the upper edges of the opposite arms 13. When in this position the coins within the holder rest at their lower edges upon the table and are raised slightly up within the members 10 and 11, whereby the same may be readily drawn snugly from the holder. The advantage of providing but two coin receiving members, and in forming the same of a length sufficient only to retain the coins in package form is that the fingers may readily grasp the coins and may operate the members to open the holders. For this reason also, the opposite edges of the arms 13 and 16 have been cut away or formed concave to disclose as far as possible the central portions of the coins.

The device is adapted to be of a predetermined length, so as to carry a predetermined number of coins, the same being of substantially the same thickness. It will also be understood that these holders or packages may be made in various sizes to accommodate coins of various diameters and thicknesses, so as to adapt the device for general use.

Having fully described our invention, what we claim is:

1. A coin holder comprising diametrically opposed coin-engaging members, inwardly projecting and overlapping arms carried on the ends of the members, rivets pivotally connecting the arms at their middle portions and locking projections carried upon the ends of the outer arms and yieldingly en-

gaging the inner arms whereby to hold the members in opposed relation, said projections also being adapted for engagement against the opposite edges of the inner arms to hold the members in offset relation whereby the coins may be supported on edge.

2. A coin holder comprising a pair of arcuate receiving members having inwardly extending and overlapping arms at their ends, said arms being pivoted together intermediate their ends, the holder having slots at its ends, the free ends of the outer arms being provided with inturned lugs yieldingly engaging in the slots whereby to hold the members in diametrically opposed position to close the holder, said arms being adapted to turn into crossed relation and hold said members in offset relation to one another whereby to open one side of the holder, said lugs being adapted for yielding engagement against the opposite edges of the inner arms to retain the holder in open position.

3. A coin package comprising a pair of arcuate coin receiving members, inwardly extending and overlapping arms carried on the ends of the members, said members having slots at their opposite ends, the outer arms having inturned projections on their outer ends engaging in said slots whereby to hold the members in diametrically opposed positions, and pivotal means holding the central portions of the arms together and admitting of the turning of the arms into crossed relation, said projections being adapted for engagement against the opposite member to hold the members in offset relation to one another.

4. A coin holder comprising a pair of offset members having inwardly extending crossed arms pivoted together at their central portions, said arms being reduced in width at their central portions and extending entirely across the ends of the holder to present uninterrupted outer and inner faces, and frictional locking means carried by the members for holding the same in various pivotally adjusted positions.
